NEEDLE VALVE HOUSING

Hisayoshi Mese, Higashi Osaka-shi, Japan, assignor to
Fuji Kinzoku Kosaku Kabushiki Kaisha, Osaka-shi,
Japan

Filed July 7, 1969, Ser. No. 18,065

Term of patent 14 years

Int. Cl. D23—01

U.S. Cl. D23—19

Fig. 1.

Fig. 2.

Fig. 3.

Fig. 4.

Fig.5.

Fig.6.

Fig.7.

FIG. 1 is a front elevation view of the needle valve housing showing the new design;

FIG. 2 is a rear elevation view thereof;

FIG. 3 is a side elevational view thereof;

FIG. 4 is an opposite side elevational view;

FIG. 5 is a top plan view thereof;

FIG. 6 is a bottom plan view thereof; and

FIG. 7 is a front perspective view thereof.

I claim:

The ornamental design for a needle valve housing, as shown.
